INVENTOR.

Joseph F. Lamb:

BY

Haast
his ATTORNEY.

UNITED STATES PATENT OFFICE.

JOSEPH F. LAMB, OF NEW BRITAIN, CONNECTICUT, ASSIGNOR TO LANDERS, FRARY & CLARK, OF NEW BRITAIN, CONNECTICUT, A CORPORATION OF CONNECTICUT.

KNIFE.

1,355,676.

Specification of Letters Patent. Patented Oct. 12, 1920.

Application filed January 31, 1918. Serial No. 214,594.

To all whom it may concern:

Be it known that I, JOSEPH F. LAMB, a citizen of the United States, and a resident of New Britain, in the county of Hartford, 5 State of Connecticut, have invented certain new and useful Improvements in Knives, of which the following is a specification.

This invention relates to new and useful improvements in knives and particularly 10 has for its object the provision of a novel form of metallic handle for a knife; novel spring construction; and other features incident thereto.

In the drawings—

15 Figure 1 is a side view of a knife with a handle shown in section.

Fig. 2 is an edge view of a knife with the part of the handle broken away to show construction.

20 Fig. 3 is a plan view of a blank utilized for making a handle.

Referring to the drawings:—*a*, denotes generally the handle; *b*, the blade; *c*, the spring; and *d*, the blade pivot.

25 The handle is formed from sheet metal and when made in two parts, as shown in Figs. 1 and 2, each half of the handle is drawn up to shape so that the drawn up edges will butt along what becomes the me-

30 dian line of the handle when seen in edge view. These two parts are conveniently secured together at one end by the pivot pin *d*; at the other end by a pin *e*. In order to give the effect of a full bolster at the blade 35 end the full width of the handle may be carried out as indicated in Fig. 2; and to supply a proper bearing for the blade, washers 5, 5, may be positioned inside of the handle at opposite sides of the blade tang.

40 The spring is of the novel form shown in the drawings and of a type which does not require any drilling to receive a rivet for holding it in place. The outer end of the spring is curved as at 9, to be seated within 45 the end of the handle and interlocked with the pin *e*. It is shouldered at an intermediate point to have a bearing on the fulcrum 10 at the back edge of the handle, and the spring blade 11 works in a slot formed 50 by cutting away the abutting edges of the two halves of the handle at the rear and toward the blade end of the knife.

It will thus be seen that the spring is held in position against movement in all direc-

tions and without the necessity of an expensive and delicate drilling and riveting operation such as is customary in the ordinary knives.

The two handle members may be assembled together and the spring introduced 60 afterward by passing its curved end back of the rivet *e*, after which the blade tang can be positioned and riveted into place. The rivet *e*, would prevent any tendency of the spring to shift toward the blade end of the 65 handle, although there is small liability of any such movement.

Handle blank of Fig. 3 is designed to produce a one-piece handle, the flanges 15, being bent over to close the end of the handle and, when properly shaped and folded together, the complete handle may be welded, soldered or otherwise united before either the spring or the blade is installed.

In accordance with the provision of the 75 patent statutes I have described the principle of operation of my invention, together with the apparatus which I now consider to represent the best embodiment thereof; but I desire to have it understood that the apparatus shown is only illustrative, and that the invention can be carried out by other 80 means.

I claim as my invention:—

A knife comprising a handle of uniform 85 thickness throughout substantially its entire length, formed from a blank of sheet metal and having a back with a slot at its forward end, and cupped sides the edges at the rear 90 ends of which are curved and abut to form a 90 curved closed rear end on the handle; a pin adjacent the rear curved end of the handle for securing the sides thereof together; a spring in the handle having a shoulder fitting against the end of the slot in the back 95 thereof, said spring having its rear end curved similarly to and seated in the curved end of said handle and interlocking with said pin; a blade having a tang positioned between the forward ends of the sides of the 100 handle and bearing against the inner face of said spring; a solid, non-yieldable washer on each side of said tang and within the recesses of the cupped sides of said handle, and a pin extending through the sides of 105 said handle, washers and tang for holding the parts in assembled position.

JOSEPH F. LAMB.
